CLAIM

The ornamental design for a clip-hanger for suspending articles from walls, as shown and described.

DESCRIPTION

FIG. 1 is a front, top and right side perspective view of a clip hanger for suspending articles from walls; showing the first embodiment of our new design;

FIG. 2 is a top plan view thereof;

FIG. 3 is a front elevational view thereof;

FIG. 4 is a right side elevational view thereof, the side opposite being a mirror image;

FIG. 5 is a rear elevational view thereof;

FIG. 6 is a bottom plan view thereof;

FIG. 7 is top plan view of a second embodiment thereof;

FIG. 8 is a front elevational view thereof;

FIG. 9 is a right side elevational view thereof, the side opposite being a mirror image;

FIG. 10 is a rear elevational view thereof;

FIG. 11 is a bottom plan view thereof;

FIG. 12 is a top plan view of a third embodiment thereof;

FIG. 13 is a front elevational view thereof;

FIG. 14 is a right side elevational view thereof, side opposite being a mirror image;

FIG. 15 is a rear elevational view thereof; and,

FIG. 16 is a bottom plan view thereof.
